UNITED STATES PATENT OFFICE.

JOHN T. LA RUE, OF PLEASANT POST-OFFICE, INDIANA.

IMPROVEMENT IN GUN-SIGHTS.

Specification forming part of Letters Patent No. 128,049, dated June 18, 1872.

Specification describing a new and useful Improvement in Gun-Sights, invented by JOHN T. LA RUE, of Pleasant Post-Office, in the county of Switzerland and State of Indiana.

This invention relates to the construction of "sights" for rifles and other fire-arms; and consists in a combination front sight and in a back sight adapted thereto, the construction of each being as hereinafter described.

In the accompanying drawing, Figure 1 is a top or plan view of the combination or front sight. Fig. 2 is a vertical longitudinal section of Fig. 1 taken on the line *x x*, showing it as when used as an open sight. Fig. 3 is a vertical section through the same line, showing it as when used as a globe-sight. Fig. 4 is a vertical cross-section of Fig. 1 taken on the line *y y*, showing it as when used as a globe-sight. Fig. 5 is a vertical cross-section on the same line, showing it closed as when used as an open sight. Figs. 6 and 7 are front and side views of the rear sight, so constructed that the front open sight can be seen through it and so that it can also be used with the front sight, Fig. 7, being a section of Fig. 6 taken on the line *z z*.

Similar letters of reference indicate corresponding parts.

A represents the bed-plate of the front sight, containing cup or cavity *B*. *C* is the front sight, which is hinged to the plate *A*, having a heel, *D*, which bears upon one end of the double flat spring *E*, seen in Figs. 2 and 3. This spring is confined to the bed-plate at the middle, as seen in those figures. *F* is a covering-plate, which bears the open sight *G*.

The front sight folds down into the cup *B*, and the plate *F* covers it, as seen in Fig. 2. This covering-plate has a heel which bears upon the other end of the spring *E*. The spring *E* acts as a friction-spring to keep the front sight in position when it is raised, its end being pressed up against the heel *D* of the front sight by the heel of the covering-plate.

By this construction it will be seen that the sight can be used either for a globe-sight or a plain open sight, the former being seen in Figs. 3 and 4, and the latter in Figs. 2 and 5.

H is the rear sight, which has an opening, *I*, (beneath the opening for the globe-sight,) through which the open sight *G* is seen. These sights are stationary, and need not be detached to adapt them for either an open or a globe-sight.

I do not limit or confine myself to the precise form or arrangements of the parts described, as variations may be made without departing from my invention.

Having thus described my invention, I claim as new and desire to secure by Letters Patent—

1. Two hinged sights, *G C*, folding one under the other upon a bed-plate *A*, as described.
2. An article of manufacture, consisting of the sights *C G*, spring *E*, and plate *A*, all relatively arranged and constructed so as to be applicable to fire-arms, as set forth.

JOHN T. LA RUE.
